PLUG-IN COIL MOUNTING

William G. Wheat, Kansas City, Mo.

Application May 3, 1934, Serial No. 723,680

1 Claim. (Cl. 175—356)

My invention relates to improvements in plug-in coil mountings used in radio communication; and the objects of my invention are, first, to provide a plug-in coil mounting of great accessibility thereby allowing a rapid change of coils, covering the different short wave bands, by the operator; and second, to provide a shielded recess well within the front of the receiver panel to give adequate coil shielding from other coils operating at similar frequency as well as other surrounding equipment; and third, to provide for a metal top or shield on the plug-in coil for the purpose of excluding dust as well as completing the metallic shield surrounding the plug-in coil.

I attain these objects by the means illustrated in the accompanying figures, in which—

Figure 1 is a front panel view of the complete plug-in coil assembly. A sectional line is drawn through the assembly, marked L—L.

Figure 2 is a top view of the plug-in coil mounting assembly showing the shield cover rigidly attached to the panel 22 and the plug-in coil, shown as Figure 5, inserted in position within the shield through the circular aperture 13, in panel 22, Figure 3.

Figure 3 is a sectional view of the plug-in coil mounting assembly taken along the section line of L—L of Figure 1.

Figure 4 shows a rear view of the plug-in coil mounting.

Figure 5 shows a side view of the plug-in coil. Number 1, Figure 1, is a small aperture beneath the coil pull handle, number 2, for the purpose of adjusting the trimmer or band spread condenser mounted inside the plug-in coil directly behind the metal cover plate and pull handle number 2. The bolts 3 and 4 hold the mounting assembly to the front of panel number 22. Numerals or colored markings on the coil top or cover, specify wave-length or frequency coverage are shown at number 5, Figure 1.

The metallic shield mounting number 6, Figure 3, is cylindrical in shape, having one end straight, the other end being flanged inward at right angles and the opening therein being equal to the outside diameter of the dust sleeve number 12, Figure 3. This is done for the purpose of securing the dust shield in position at the front or panel end of the shield. The said opening in the end of the shield being slightly larger than the circular aperture through the panel face so as to allow the dust shield to slide through the shield opening and butt up against the inside of front panel number 22. The shield can assembly is

rigidly bolted to the panel by bolts or rivets number 3 and number 4. A flanged bottom or base, number 7, is fitted inside the shield can number 6 and is held in place by rivets number 8. The multi-pronged socket base, number 9, is held in position by the bracket number 10 which is securely fastened to the base, number 7, by bolting or riveting.

The socket base, number 9, has a projecting surface area, number 11, composed of any type of insulating material, disc-like in shape, over the outer edge of which fits the dust sleeve, number 12, which is of some non-metallic substance such as bakelite or fibre. The forward end of the sleeve rests against the inner lip of the circular panel aperture, number 13, and is held in alignment by the forward circular aperture in the metallic shield can, number 6.

The small openings shown at numbers 14, 15, 16, 17, 18, and 19, Figure 4, are for the passage of the necessary connecting cables to the socket base.

A section of the plug-in coil with its metallic pull handle and metallic shield cover and non-metallic dust cover is removed to show the assembly of a trimmer condenser, number 20, Figure 5. Any material for the plug-in coil form may be used, such as bakelite, isolanite, etc. To give additional protection against the collection of dust or mechanical damage to the winding of the coil a non-metallic sleeve, number 21, Figure 5, may be placed over it, extending the full length of the coil.

It is a well known fact that the old method of mounting the plug-in coil inside the radio receiver necessitated raising the lid of the cabinet, removing the coil shield cover—if shielded—and then removing the coil. If the coil prongs stuck somewhat, the radio receiver, if not securely bolted to the operating table, was, in many cases, lifted therefrom to fall back with a jolt, which was not conducive to long life of the tubes and other parts.

To replace the coils it was necessary to do so by touch alone as the interior of the cabinet was usually dark and the holes in the socket base could not be seen. It was at about this stage that the crowning mishap usually occurred. The headphones, if not well balanced on the operator's head, slid off into the receiver thereby causing damage if they struck any of the equipment therein. However, the worst feature of the old type of interior coil mounting was the loss of time in making the coil change.

In the panel mounted type of coil this is not

true for with the simple insertion of a finger through the coil pull ring and the placing of a thumb against the panel face the coil comes out quickly. It is easy to replace for the aperture in the panel is about on a level with the operator's eyes, and after meshing the contact points a slight push engages the coil.

While I have shown and described what I consider the preferred embodiment of the invention, I desire to have it understood that I do not limit myself in this connection, and that such changes may be resorted to, when desired, as fall within the scope of what is claimed.

What is claimed is:

15 In combination, a panel having an aperture

therein, a metallic shield can rigidly attached to the rearward side of the panel opposite aperture within said panel, a dust shield secured between rear side of panel aperture and rear portion of shield can structure, a coil assembly removable through said panel, said assembly including a coil form, a non-metallic close fitting dust cover rigidly secured over the coil form, a variable condenser mounted in the upper end of said coil form and having an adjusting screw, 10 and a metallic shield end cover for the coil assembly apertured opposite the adjusting screw of the condenser.

WILLIAM G. WHEAT.
